UNITED STATES PATENT OFFICE.

JACK W. CHOW, OF LODI, CALIFORNIA.

RACK ATTACHMENT.

Application filed November 3, 1927. Serial No. 230,834.

This invention relates to a hat supporting attachment or rack especially adapted to be used upon the swinging seats of theatre or similar chairs and it consists in the novel 5 features hereinafter described and claimed.

An object of the invention is to provide a rack of simple structure adapted to securely hold a hat beneath the seat of the chair and having means whereby the rack may be swung 10 from a position for the insertion of the hat therein to a position whereby the hat is held in close proximity to the under surface of the seat of the chair.

A further object is to provide a hat supporting rack of this character which is hingedly mounted upon the seat of the chair for swinging movement in a vertical plane and which is connected to a lever disposed adjacent the front of the chair so that by merely 20 swinging the lever the rack may be swung from a vertical receiving position to a horizontal holding position or vice versa.

A still further object is to provide means for engaging the brim of the hat and holding 25 it clamped in place so that the hat cannot slip out of the rack or holder.

In the accompanying drawing:—

Figure 1 is a side elevation view showing 30 the rack applied to the chair;

Figure 2 is an under plan view of the same; 35 Figure 3 is a detailed fragmentary sectional view.

As illustrated in the accompanying drawing, the said seat panel to which the rack is applied is of conventional form and shown at 40 1. A rack frame 2 is hingedly connected by means of spring hinges 3 with the under surface of the seat panel 1. The sides of the frame 2 are spaced from each other. A hat retaining frame 4 of wire and of usual form is connected at its ends with the side portions of the frame 2 and bridges the space between the said sides. A bell crank lever 5 is pivotally connected to the under side of the said panel 45 1 in the vicinity of the end of one of the sides of the frame 2. The said side is provided at its side edge with a bearing 6. The bearing 6 is adjacent one of the hinges 3 which connects the said frame with the said panel. A link 50 7 is pivotally connected at one end with the bearing 6 and pivotally connected at its other end with the shorter arm of the bell crank lever 5.

When the longer arm of the lever 5 is swung 55 away from the under surface of the seat panel

1 the link 7 moves longitudinally and its outer end passes transversely across the axis of the pivot which connects the lever 5 with the said panel. At the same time the said link 7 swings the frame 2 with which it is connected. 60 During this swinging movement the inner end of the link 7 moves transversely under the axis of the pivot by means of which the attached frame 2 is connected with the seat panel. Therefore, the said bell crank lever and the link serve as means for holding the frame 2 in close proximity to the under surface of the said panel. When pressure is applied to the longer end of the lever 5 and the said end is moved forwardly, the link 7 is 65 moved in an opposite direction to that hereinbefore described whereby the frame 2 is swung away from the seat panel. When the seat panel is down or substantially horizontal with relation to the chair of which it is a part 70 and the frame 2 is swung away from the panel the frame 4 is disposed substantially in a vertical position and a hat may be readily inserted therein. Then by swinging the longer end of the lever 5 inwardly under the seat 75 panel the frame 2 is swung up toward the under surface of the seat panel and secured as hereinbefore described. Thus it is possible to place the hat in the rack and dispose the hat under the seat panel without raising the 80 seat panel. Also by swinging the bell crank lever forwardly the hat is removed from under the seat panel and drawn to the forward portion thereof and may readily be extracted from the frame. 85

A curved lever 8 is pivoted to the frame 2 and is provided at one end with a cork tip 9. A rod 10 is pivotally connected at one end with the lever 8 and its opposite end passes through an eye 11 attached to the under side 90 of the seat panel 1 at a point to one side of a line coincident with the axes of the hinges 3. A spring 12 bears at one end against the side of the eye 11 and at its other end against the rod 10 and serves as means for resiliently 95 holding the rod inwardly when the seat panel is swung to the horizontal position as shown in Figure 1 of the drawing. When the seat panel is swung to the vertical position as shown in dotted lines in Figure 1 the rod 10 100 draws the lever 8 to an open position so that the edge of the hat which is inserted in the frame 4 lies adjacent the tip 9 of the lever 8. When the rack is swung from the position 105 shown in dotted lines in Figure 1 to the position 110 shown in Figure 2 the rod 10 bears against the side of the eye 11 and holds the lever 8 in the position shown in Figure 2.

tion shown in full lines the lever 8 is swung by the rod 10 whereby the tip 9 engages the end of the hat and prevents the same from falling out of the frame 4.

5 Having described the invention what is claimed is:—

10 1. A rack attachment for a chair comprising a rack frame hingedly connected with the frame, a hat frame carried by the rack frame, means for swinging the rack frame with relation to the chair, a curved lever pivoted to the rack frame, an eye attached to the chair at a point to one side of a line coincident with the axes of the hinges of the rack frame, a rod connected at one end with the lever and passing through the eye and a spring bearing at one end against the eye and at its opposite end against the rod.

20 2. A hat holding attachment for chairs having a seat comprising a hat supporting frame, spring hinges connecting the forward end of the frame to the under side of the seat, the hinges normally urging the frame toward a horizontal position, a bell crank lever pivotally supported upon the under side of the seat at the forward edge thereof, and a link pivotally connecting the bell crank lever to the frame at a point adjacent the hinge but in advance thereof.

30 3. A hat holding attachment for chairs comprising a hat holding frame hingedly connected with the chair, manually operable means for swinging the hat holding frame in a vertical plane from a vertical position to an approximately horizontal position beneath the seat of the chair, a hat brim clamp mounted upon the frame, and means for automatically closing the hat brim clamp toward the frame when the frame is moved to a horizontal position and automatically opening the clamp when the frame is lowered to a vertical position.

40 4. A hat holding attachment for chairs comprising a hat holding frame hingedly connected with the chair, manually operable means for swinging the hat holding frame in a vertical plane from a vertical position to an approximately horizontal position beneath the seat of the chair, a hat brim clamp comprising an angular lever pivotally mounted upon the frame at the rear end thereof and having a pad at one end, a rod attached at one end to the other extremity of the lever from said clamp and extending parallel to

55 the frame, and a spring engaging the forward end of the rod and yieldingly urging the rod in a direction to cause the clamp to move toward the frame and causing the rod to move upward to thereby release the clamp when the frame is moved to a vertical position.

60 5. The combination with a seat, of a hat holder hinged to the forward margin of the seat for vertical movement beneath the seat and independent thereof and swingable from a horizontal position to a vertical position and vice versa, and manually operable means for swinging the hat holder into these positions and holding the holder in a raised position.

65 6. The combination with a chair having a seat, of a rack attachment comprising a rack frame hingedly connected to the forward margin of the seat for movement in a vertical plane beneath the seat from a position depending from the seat to a position approximately parallel thereto, a lever pivoted upon the seat at the forward end thereof and a link pivotally connected at one end of the lever and at its other end to the rack frame.

70 7. The combination with a chair having a hat holding attachment comprising a rack hinged at its forward end to the forward end of the seat for a movement in a vertical plane beneath the same, a hat supporting frame mounted upon the rack, a spring urging the rack toward a horizontal position beneath the seat of the chair and parallel thereto, and means mounted upon the chair for swinging the frame from its horizontal position to a vertical position or vice versa independently of the chair seat.

75 8. The combination with a chair having a seat, of a hat holding attachment comprising a rack, spring hinges hingedly connecting the forward end of the rack to the forward end of the seat below the same, a hat holder mounted upon the frame and movable therewith, a bell crank lever pivotally supported upon the seat beneath the forward end thereof and a link pivotally connecting one arm of the lever to a rack adjacent its hinged end, whereby the rack may be swung to a position parallel to the underside of the seat to a depending position or vice versa.

80 In testimony whereof I hereunto affix my signature.

JACK W. CHOW.
